UNITED STATES PATENT OFFICE

2,489,046

GARMENT HOLDER

Rose H. Odell, Corpus Christi, Tex.

Application November 23, 1945, Serial No. 630,170

1 Claim. (Cl. 2—229)

1

My invention relates to a device to hold a skirt and blouse in proper position on the person of the wearer.

The main object of the invention is to prevent a blouse from slipping out from underneath the skirt band, when the two garments are worn together.

Another object of the invention is to arrange means for keeping blouse and skirt in proper relationship to each other when being worn so that said means will be invisible.

Other objects of my invention may appear in the following specification describing my invention with reference to the accompanying drawings forming a part thereof. It is however to be noted that my invention is not to be limited or restricted to the exact construction and combination described in the specification and shown in the drawings but that such changes and modifications can be made which fall within the scope of the claim appended hereto.

In the drawings:

Figure 1 is an illustration of a part of my invention destined to be sewn on to the back of a blouse.

Figure 2 is an illustration of a second part of my invention destined to be sewn onto the back of a skirt band.

Figure 3 is an illustration of a part to be sewn onto the side of a blouse.

Figure 4 is an illustration of a part to be sewn onto the side of a skirt band.

Figure 5 is a sectional view showing the cooperating parts of my invention in position on a blouse and a skirt, and

Figure 6 is a sectional view taken on line 6—6 in Figures 1 and 2, the two parts illustrated in these figures being shown in operative position.

Referring to the drawings a piece of twill tape 19 is folded lengthwise in the middle as shown at 18 in Figure 5. The tape is sewn together, the ends of the tape being folded under. The length of the tape is preferably 3½ inches. As shown in Figure 1, three eyes are sewn onto the tape, one in the center and one of the other two adjacent each end of the tape. This tape is then sewn onto the back of a blouse, the eyes outside and the open end of the eyes up as shown at 12 in Figure 5.

Another piece of twill tape 13 is folded lengthwise in the middle and three pieces of elastic tape 14, preferably 2½ inches long are folded crosswise in the middle. The folded ends 15 of the elastic tape are arranged between the folded parts of the twill tape 13 and are fastened there by sewing these last named two folded parts and the elastic tape together. The ends of tape 13

2

are folded under before the sewing is done. The elastic tape is so arranged that the position of the folded over ends 15 in the twill tape 13 will correspond with the position of the eyes 12 on tape 10. Hooks 16 will be sewn onto the twill tape 13, the position of the hooks 16 on tape 13 corresponding with the eyes 12 on tape 10. The hooks point downwardly and the upper end of the hooks are located below the top edge of twill tape 13.

10 Then another piece of twill tape 17 of the same length as the tapes 10 and 16 is folded lengthwise in the middle and the free ends 18 of the elastic tapes 14 are placed between the folded over halves of tape 17 and these halves and the elastic tapes 15 are sewn together. The ends of tape 18 are folded under before the sewing is done.

The tape 17 is sewn onto the back of a skirt band on the inside as shown at 19 in Figure 5. The tape 13 supporting the hooks 16 is then located above the tape 17 and is loose. The hooks 16 are located so that they can engage the eyes 12.

20 Tape 17 is sewn onto the skirt band so that the top edge of twill tape 13 will be located approximately ½ of an inch below the top edge of the skirt band and that the hooks 16 will be in position to engage the eyes 12 when the garments are worn together.

25 In Figure 3 another combination of a twill tape 20 and eyes 21 is shown and this combination is put together exactly in the same way as the combination shown in Figure 1 and described above. The only differences between the two combinations are that the one shown in Figure 3 has a shorter twill tape and that preferably only two eyes are used. Of this combination two are required and one of them is sewn onto each side of blouse at the same level as the combination shown in Figure 1.

30 In Figure 4 a combination of a twill tape 22, elastic tapes 23, a second twill tape 24 and hooks 25 is illustrated and this combination is put together exactly like the one shown in Figure 2 and described above, but the twill tapes 22 and 24 are of the same length as the length of twill tape 20

35 in Figure 3 and only two hooks 25 are preferably used. Of this combination two are also required and one of them is fastened on a skirt band at each side thereof. They are fastened to the skirt band by sewing the tape 24 onto it so that the top edge of the other tape 22 will be located at the same level as the top edge of the combination shown in Figure 2, and that the hooks 25 will be in position to engage the eyes 21 on the blouse.

40 From the above description it will be understood that a blouse, equipped with the eye ar-

rangement according to my invention, worn in combination with a skirt having my hook arrangement thereon, can be secured against slipping out of the skirt band, and it will be further understood that blouses and skirts can be easily and cheaply fitted out with the equipment of my invention.

Having described my invention, what I claim and desire to secure by Letters Patent is:

Means for retaining the bottom of an upper garment within a lower garment waist band comprising a doubled over strip of tape attachable to one of said garments, strips of elastic webbing spaced apart longitudinally of said tape strip and extending outwardly from the open longitudinal edge of the latter, each of said elastic strips being secured near one end between the folds of said tape strip, a second, double over tape strip spaced from said first mentioned tape strip and substantially parallel to the latter, the ends of said elastic strips opposite said first mentioned tape strip being secured between the folds of said second tape strip, a third, doubled over tape strip attach-

able to the other of said garments, and separable fastener components secured on said second and third tape strips to detachably connect the portion of said retaining means attachable to one garment to that portion of the retaining means attachable to the other garment.
